UNITED STATES PATENT OFFICE

JOHN G. CLEMENS, OF EGGERTSVILLE, NEW YORK, ASSIGNOR TO PIERCE RENEWABLE FUSES, INC., OF BUFFALO, NEW YORK

REFILLABLE FUSE

Application filed January 25, 1927. Serial No. 163,411.

This invention relates to refillable fuses of the kind having a fuse link which when burned out can be replaced by another fuse link.

5 Fuses of this kind as heretofore made have generally been provided with a body portion made of fiber or other insulating material, which while not readily combustible, is nevertheless damaged or charred by flame resulting from the burning of the fuse link and also by the heat generated in the fuse link, so that the body portions of these fuse links eventually become weakened due to charring of the material of which the body portions 10 are made. To make these body portions of non-combustible insulating material involves difficulties in that such material ordinarily cannot be provided with screw threads and cannot be bored or machined in such a manner as to provide ventilating passages for the 15 gaseous products of combustion resulting from the blowing of the fuse link.

The objects of this invention are to provide a fuse of this kind made entirely of non-combustible material or material which is not damaged by the temperatures resulting from the blowing of a fuse link; also to provide a fuse of this kind in which a chamber or passage for the gaseous products of combustion 20 is provided in a metallic portion arranged exterior to the non-conducting body of the fuse; also to provide a fuse of this kind with means of novel construction for securing the ends of the removable fuse link to metallic 25 terminals of the fuse; also to provide the insulating body portion of the fuse with means of improved construction by which the fuse may be handled without touching the conducting portion of the fuse; also to improve 30 the construction of fuses of this kind in other respects hereinafter specified.

In the accompanying drawings,

Fig. 1 is a longitudinal, central sectional elevation of a refillable fuse embodying this 35 invention.

Fig. 2 is a side view of the body of the fuse.

Fig. 3 is a side view, on a reduced scale, of the completed fuse.

50 Fig. 4 is a fragmentary, sectional view of a fuse showing the several parts of the fuse

separated from each other to show their structure and the manner of assembling the fuse.

Fig. 5 is a transverse, sectional elevation of the fuse on line 5—5, Fig. 1.

Fig. 6 is a longitudinal section of a body of modified construction.

A represents in general the tubular shell or body of the fuse which is made of insulating and non-combustible material. Lava has been found to be highly satisfactory for this purpose, but other materials may be employed in forming the body portion. If the body portion is made of lava or similar non-combustible insulating material, it is not practical to do any intricate machine work on the body portion and also it is not possible to form these body portions in molds which are intricate, since this material cannot readily be forced into crevices or recesses in such molds. The barrel or body portion of the fuse, as shown in Figs. 1-5, includes the usual tubular portion *a*, and a radially extending integral flange *a'*, which serves as a finger hold for the fuse. The insulating body of the fuse is also provided with a portion which is adapted to hold the metallic parts of the fuse securely in place on the body. For this purpose, in the particular construction shown, an annular shoulder *a*² is formed near each end of the tubular portion *a*, the shoulder *a*² being formed by means of an annular groove 55 extending around the tubular portion *a* of the body or housing A. In order to prevent rotation of the shells or metal portions of the fuse on the body, the tubular portions *a* of the body are provided with longitudinal 60 grooves or keyways *a*³ in the outer surfaces thereof, which cooperate with corresponding parts, hereinafter to be described, on the metal portions of the fuse. Any other projections or depressions on the body portion for holding the metal portions of the fuse against endwise displacement and against 65 turning thereon may be provided.

In order that a fuse of this kind may be able to withstand tests and inspection while the fuse link is burned by a severe overload of electric current, it is desirable that means be provided for causing the gaseous products of combustion, after flowing outwardly in op- 70

posite directions from the tubular portion a of the body of the fuse, to flow back in the opposite direction in another passage before being discharged to the atmosphere, a vent member or shell is provided around the body of the fuse, which in the particular construction shown is in the form of two tubular shell parts B and B' , arranged at opposite sides of the flange portion a' , and these shell parts may be of any suitable construction. In the particular fuse illustrated in the drawings these parts are made with an inner wall b arranged in close proximity to the tubular portion a of the body of the fuse, and an outer wall b' arranged substantially concentric with the wall b and spaced therefrom, and, if desired, a mass of wire gauze or other porous material C may be inserted in the annular vent passage or space between the two annular walls b and b' . This annular vent space opens toward opposite ends of the fuse and communicates with the interior of the tubular portion of the body of the fuse. The outer wall b' is provided with a number of holes or discharge orifices b^2 through which the gaseous products of combustion after passing through the screening material C are discharged to the atmosphere. The outer end of the wall b' is preferably screw threaded internally to receive another part of the fuse, to be herein-after described. The inner wall b of each shell preferably also has longitudinal inwardly extending projections b^4 extending into the keyways a^3 on the body portion when the shell is placed on the body. When these shells are applied to the body A , the inner ends of the inner wall b are pressed or spun inwardly toward each other as shown at b^3 in Fig. 1, so that these inner ends extend toward each other and abut against the shoulder a^2 of the insulating body to secure the vent shells on the body of the fuse. Other means for supporting the vent shells on the body of the fuse may, of course, be employed, if desired.

D represents the fuse link which may be of any suitable or desired form, and in order to clamp the ends of the fuse link to the contacting or terminal parts of the fuse, bushings E and E' are preferably provided which may be suitably held on the fuse and which have faces against which the turned over end portions of the fuse link may be clamped. In the particular construction shown, these bushings E , E' are provided with outer screw threaded portions e adapted to engage with internally threaded portions b^5 of the vent shells B , B' of the fuse. The threaded portion e terminates in a shoulder e' which limits the extent to which the bushings E , E' may be screwed into the vent shells B , B' , and the ends of the bushings E , E' preferably serve to engage the gauze or porous material C to

hold the same in place. If desired, the bushings E , E' may be permanently secured to the vent shells B , B' in any suitable or usual manner, for example by pins e^2 passing through the threaded portions of these two parts. The outer peripheries of the bushings E , E' beyond the shoulders e' are provided with screw threads e^3 which are adapted to cooperate with corresponding screw threads f on the terminal members or ferrules F , F' of the fuse. These ferrules or terminal members F , F' may be of any suitable or desired kind, adapted to contact with fixed parts or clips (not shown) for connecting the fuse in a circuit. The inner faces of the caps F , F' are adapted to cooperate with the outer faces or ends of the bushings E , E' so that the ends of a fuse link may be clamped between these two faces as clearly shown in Fig. 1.

In the modified construction shown in Fig. 6, the body G of the fuse is made tubular throughout and the finger hold portion of the fuse is in the form of a ring g of insulating material made separate from the body and fitting around the same. This finger hold ring is consequently held in place on the body of the fuse by the shells B , B' when the same are assembled on the body. The body G shown in Fig. 6 may be used in place of the fuse body A shown in the other drawings.

When the fuse is assembled as shown in Figs. 1 and 3, substantially all of the body portion of the fuse will be covered by metal with the exception of the annular flange a' or ring g , which afford a finger hold by means of which the fuse may be moved into and out of its operative position, so that the user of these fuses need not come into contact with any metallic parts connected with the circuit. By means of the construction described, all of the products of combustion resulting from the blowing of the fuse link are forced outwardly through the opposite open ends of the tubular portion a of the body of the fuse, and the heavy portions of material, such as pieces of molten metal will continue to move in this direction and will strike and be deposited on the inner faces of the ferrules F , F' , while the lighter products of combustion, such as the gases, will flow in the reverse direction into the annular space between the inner and outer walls b and b' of the metallic shell B , and thence through the gauze or porous material C and out of the discharge holes or openings b^2 . By deflecting the gases and separating the same from the solid particles of material, there will be no tendency of the gauze or porous material to become plugged or filled up with particles of solid matter, and the gaseous products of combustion will be amply cooled during their passage through the gauze or porous material and will emerge from the holes b^2 sufficiently cool to be absolutely safe. The fuse link may

be burned repeatedly without causing any damage whatever to any portion of the fuse, since the body portion which is subjected to the greatest heat, is made of non-combustible material, and also the heat developed in the fuse link during the normal use thereof will not tend to char the body portion of the fuse, so that the fuse may be used indefinitely without being weakened or damaged in any manner.

10 I claim as my invention:—

11 1. A refillable fuse including a substantially tubular body of non-combustible insulating material having annular shoulders, a 15 fuse link extending through said body, vent shells arranged about said body and having passages extending lengthwise of the outer surface of said body for the gaseous products of combustion resulting from the fusing of 20 said link and having portions pressed into engagement with said shoulders to secure said vent shells to said body, and means connected with said vent shells to secure the ends of said fuse link thereto.

25 2. A refillable fuse including a substantially tubular body of non-combustible insulating material, a fuse link arranged in said tubular body, terminal members with which the ends of said fuse link are connected and which 30 are supported on said body, a pair of vent shells mounted on said body and communicating with the opposite ends of said body to receive gaseous products of combustion therefrom and discharge the same to the atmosphere, said shells having parts which are 35 pressed into locking engagement with corresponding parts on said body.

3. A refillable fuse including a substantially tubular body of non-combustible insulating material, a fuse link extending lengthwise through said body, a pair of metallic vent shells mounted on said body and having vent passages communicating with the opposite ends of said body to receive gaseous 45 products of combustion from the ends thereof and conduct the same in a reverse direction along the periphery of said body to the atmosphere, and contact means supported on said body and with which the ends of said 50 fuse link engage.

4. A refillable fuse including a substantially tubular body of non-combustible insulating material, a fuse link arranged in said tubular body, a pair of metallic shells mounted 55 on said body and having annular vent passages arranged substantially concentrically about said body and communicating at their outer ends with the opposite ends of said body to receive gaseous products of combustion 60 therefrom and discharge the same adjacent to their inner ends to the atmosphere, and terminal members with which the ends of said fuse link are connected and which are supported on said vent shells.

65 5. A refillable fuse including a substantial-

ly tubular body of non-combustible insulating material, a fuse link arranged in said tubular body, terminal members with which the ends of said fuse link are connected and which are supported on said body, a pair of metallic vent shells extending about said body and having an inner wall arranged adjacent to the outer wall of the tubular portion of the body, and an outer wall spaced at a distance therefrom to form a annular vent passage 75 through which products of combustion pass from the ends of said tubular body, said outer walls of said vent shells being provided with apertures through which products of combustion pass to the atmosphere.

80 6. A refillable fuse including a substantially tubular body of non-combustible insulating material, a fuse link arranged in said tubular body, terminal members with which the ends of said fuse link are connected and which are supported on said body, a pair of metallic vent shells extending about said body and having an inner wall arranged adjacent to the outer wall of the tubular portion of the body, an outer wall spaced at a distance 85 therefrom to form an annular vent passage through which products of combustion pass from the ends of said tubular body, said outer walls of said vent shells being provided with apertures through which products of 90 combustion pass to the atmosphere, and a shoulder near each end of said body, the inner wall of each of said vent shells being pressed into engagement with said shoulder to retain the vent shells on said body.

95 7. A refillable fuse including a substantially tubular body of non-combustible insulating material, metallic vent shells extending around parts of said body and adapted to receive products of combustion discharged 100 from the ends of said body, bushings secured to said shells, ferrules, each having a threaded engagement with a bushing, and a fuse link extending through said body and having its ends secured between said bushings 105 and said ferrules.

110 8. A refillable fuse including a substantially tubular body of non-combustible insulating material and having an integral outwardly extending annular flange arranged intermediate of the ends of said body, metallic vent shells mounted on opposite sides of said flange and surrounding said body and provided with passages communicating with the ends of said body for receiving products of combustion and discharging the same to the atmosphere, a fuse link extending through said body, and terminals mounted on said metallic shells to which the ends of said fuse link are secured.

115 9. A refillable fuse including a substantially tubular body of non-combustible insulating material and adapted to contain a fuse link, metallic members secured to and arranged about the walls of said body and hav-

ing vent passages communicating at their outer ends with the ends of said body and having vent openings near the inner ends of said members, and an annular member of insulating material projecting outwardly from said body and spaced between the inner ends of said metallic members.
